RAILROAD CAR

Otto A. Kuhler, Blauvelt, N. Y., and William E. Burnett, Montclair, N. J., assignors to American Car and Foundry Company, New York, N. Y., a corporation of New Jersey

Application April 11, 1947, Serial No. 740,744

8 Claims. (Cl. 105—315)

1

This invention relates to railway cars and more particularly to sleeping cars.

The present trend in the design of sleeping cars is to provide private rooms for all of the passengers and the general plan has been to arrange the rooms on a single deck. Such arrangement reduces the number of passengers that can be accommodated as compared with previous single deck structures having upper and lower berths. As a consequence, the fare for private rooms has been much higher in order to give the carrier the same revenue per car as that previously realized and necessary for profitable operation.

An object of the invention is to utilize the spare space to a maximum extent in stairway terminal rooms of a two deck sleeping car as storage chambers.

Another object of the invention resides in the arrangement and formation of a room and seat whereby the seat can be extended to horizontal bed position in a room having the major portion of its length less than that of the bed.

A further object of the invention is to provide a sleeping car, of the private room type, with adequate accommodations for the porter, baggage, equipment and accessories.

These and other objects of the invention will be apparent to those skilled in the art from a study of the following description and accompanying drawings, in which:

Figure 1 is a side elevational view of a sleeping car incorporating the invention.

Figure 2 is a sectional view of the car taken on line 2—2 of Figure 3.

Figure 3 is a sectional view of the car taken on line 3—3 of Figure 2.

Figure 4 is a sectional view of the car taken on line 4—4 of Figure 3.

Figure 5 is a sectional view of the car taken on line 5—5 of Figure 2.

Figure 6 is a sectional view of the car taken on line 6—6 of Figure 4.

Referring now to the drawings by characters of reference, the sleeping car indicated generally by numeral 10 is mounted upon a pair of wheel trucks 11 located one near each end thereof. The car flooring is arranged in three levels, the end floorings 12 being arranged to overlie the trucks. A lower flooring 13 extends horizontally between the trucks and in a plane slightly above the track rails 9 on which the truck wheels 14 ride. This lower flooring is below the end floorings and is connected therewith by floor portions 15. Extending in a horizontal plane above the end floorings and over the lower flooring is an upper floor-

2

ing 16. The car is provided with a conventional roof structure 17 and outer side walls 18.

A pair of spaced panels 20 extend centrally and longitudinally of the lower flooring and are suitably attached to the lower and upper floorings 13 and 16 and provide therebetween a center aisle 21.

The longitudinally extending spaces between the panels 20 and the car sides are divided into rooms, preferably of similar length, by transversely extending panels 22.

10 Centrally located spaced panels 23 extend longitudinally above the upper flooring 16 providing a center aisle 32 which is closed at the ends by bulkheads 19. These upper panels 23 are preferably in alignment vertically with the lower panels 20.

15 The longitudinally extending spaces between the upper panels and the car side walls 18 are divided into rooms by transversely extending panels 24 arranged preferably substantially the same distance apart. Such transverse panels are suitably secured to the roof, the upper flooring, the car outer side walls and the panels 23 to provide a series of compartments or rooms along each side of the upper aisle.

20 Spaced panels 25, located centrally of the car, extend longitudinally from the end transverse panels 22 and 24 of the lower and upper decks to the adjacent vestibule portions 25 of the car. These panels 25 are in line longitudinally of the car with panels 20 and 23 and form a central aisle

25' that aligns with the central aisle of the lower flooring. The spaces between the car side walls and panels 25 are divided into room spaces by transverse panels 57. Below the roof and over each of the end floorings is arranged a ceiling member 27 providing end chambers 28 for accommodating heavy equipment and accessories.

30 The floor portions for the rooms adjacent the flooring connections 15 are in a plane slightly above the balance of the end floorings. Steps 31 are carried by the dependent connections 15 and lead from end flooring aisles 25' to lower aisle 21. The bulkheads 19 are short of the ends of the upper flooring and the upper flooring between panels 23 beyond the bulkheads is cut away to

35 provide head room for persons standing in aisle 21 adjacent the bottom of steps 31.

40 Room 33 is provided with a transverse panel 34 providing a toilet room 35, such panel having an entrance opening with a sliding door 36.

45 Panel 25 has an archway open to room 33 and this room contains a water cooler 37, provides a storage space and a foyer. This room also has a longitudinally extending panel 38 therein and steps 39, supported between this panel and the

50 55

adjacent aisle panel, lead from room 33 to the end upper room 40 adjacent thereto. The end transverse panel 24 has an archway 41 above the head of such steps while panel 23 for room 40 has an archway 42 open to the upper aisle. A transverse door 43 in room 40 closes baggage chamber 44 and longitudinally extending panel 45 forms a locker 46. Door 46' closes an opening in panel 45.

Room 47 on the inner end of the end flooring 10 at the other end of the car and on the opposite side of the aisle from room 33, has a longitudinal panel 48 extending the entire length thereof of forming a locker 49 for electric equipment. Door 50 provides access to the electric equipment locker and archway 51 is provided in panel 25 for openly connecting room 47 and the adjacent center aisle 25'. Steps 52 lead from room 47 to the adjacent end room 53 on the upper deck and the end transverse panel 24 has an archway 54 above the top of the steps. Panel 23 for room 53 has an archway 55 leading to the upper deck center aisle. This room 53 also provides storage chambers 80 and 81 for various car accessories or equipment. Door 52 opens to provide access to chamber 80 and door 83 opens to provide access to chamber 81. The steps 39 and 52 are arranged on opposite sides of the center aisle so that a passenger will leave the center aisles in passing from one to the other. The ceilings 27 extend 30 horizontally above the end floorings except over the steps 38 and 52 where portions 56 thereof extend upwardly toward end panels 24 of the upper deck to provide head clearance. Openings in ceiling portions 56 providing access to chambers 28 are closed by doors 85. Chambers 28 are also accessible through openings in the end panels 24 accessible from aisle 32 and closed by doors 86 and accessible from upper end rooms and closed by doors 87. As there are bulkheads at 40 the ends of the upper aisle, the side steps between upper and lower rooms provide the only access between the upper aisles and the center aisles of the end floorings. The advantage of this type of construction is to eliminate the general passage of persons through the upper aisle of the car whereby the passengers in the upper rooms are not disturbed by general traffic through the car.

The room spaces throughout the car have the same length except room space 47 and the room 60 across the hall therefrom, such rooms being of less length than required for a sleeping room. It is proposed to utilize room 69 for the porter and in order to provide regulation length for bed means, the adjacent end panel 22 of the lower deck is formed with a well 61 open to room 60. Such well may be formed by depressing the panel or by the application of enclosure members around an opening in the panel. The well projects into the adjacent lower deck room 62 which may be utilized as a storage chamber for car batteries.

Adjacent the aisle panel in the room 60 for the porter is an enclosure wall 63 forming a closet 64. Between the closet and the side wall of the car is arranged a chair structure that may be made up into a bed. The chair seat structure 65 is supported on pedestal 66 when used as a chair and on brackets 67 fixed to the transverse panel at the forward end of room 60 and brackets 67' fixed to walls 18 and 63 when used as a bed. The back structure 69 is removable and can be laid horizontally on the pedestal and the bottom wall of the well 61. As a bed consisting of the chair seat and

5 back may lack regulation length, a sponge rubber pad 90 in the well furnishes an extended bed surface and with the seat and back forms the bed means for the porter. The well also serves as a chamber for storing the bed mattress, covers and pillows when the back structure and seat structure are in chair forming position.

A panel 68 extends across the room 60 above the chair back and forms a linen locker 70 accessible to the porter from within his room. A suitable door 71 is provided to close an opening in the locker panel.

The rooms, other than those referred to specifically, provide private bedrooms in which are arranged a bed 72, a chair 73, wash basin 74 and other usual accommodations. The aisle panel for each of these bedrooms and the porter's room have an opening adapted to be closed by sliding doors 75. The ends of aisles 25' are closed by doors 88 slidably transversely in a pocket in end panel 57.

It will be understood that the car outline comes within dimensions required in the railroad industry. A maximum number of passengers are accommodated in the car and substantially all other available space is utilized for the adequate storage of car equipment, accessories and baggage.

The invention may be modified in various respects as will occur to those skilled in the art and the exclusive use of all modifications as come within the scope of the appended claims is contemplated.

What is claimed is:

1. In a railway sleeping car, a flooring, a roof, side walls, spaced longitudinally extending panels forming an aisle, transverse panels dividing the spaces between the panels and car side walls into rooms, a seat structure in one of the rooms having a forwardly shiftable seat cushion and a back cushion shiftable for alignment horizontally with the seat cushion to form a portion of a bed, and a well extending into the room adjacent the back cushion for accommodating and supporting an end portion of the back cushion when moved to horizontal bed forming position.

2. In a railway sleeping car, a flooring, a roof, side walls, spaced longitudinally extending panels forming an aisle therebetween, transverse panels 50 dividing the spaces between the longitudinal panels, and the side walls into room spaces, a longitudinal panel in one room adjacent the aisle panel forming therewith a closet, a seat structure in one end of said room between the closet panel 55 and the side wall having a stationary base, a horizontally shiftable seat on the base and a removable back cushion, a well on the transverse panel adjacent the chair structure projecting into the adjacent room with the bottom thereof in longitudinal alignment with the seat cushion when in horizontal position with the seat moved forward, said back cushion being supported at one end on the floor of the well and at the other end on said base, and means in the room for supporting the seat cushion in forward shifted bed forming position.

3. In a railway sleeping car, a flooring, a roof, side walls, spaced longitudinally extending panels forming a center aisle therebetween, transverse 70 panels dividing the spaces between the longitudinal panels and the adjacent car side walls into rooms, and means on one of said panels forming two oppositely extending chambers both accessible from one of said rooms.

75 4. In a railway sleeping car having wheel trucks

near the ends thereof, a roof, side walls, end floorings over the trucks, a bottom flooring between the trucks, an upper flooring between the trucks over the lower flooring and in a plane above the end floorings, spaced longitudinally extending panels on each of said floorings forming center aisles therebetween and side spaces, bulkheads at the ends of the aisle of the upper flooring, transverse panels dividing the side spaces into rooms, central stairways between the ends of the center aisles of the lower flooring and the end floorings, and stairways between opposite aisle panels for the end floorings and the adjacent side wall leading from rooms on the end floorings to end rooms on the upper flooring.

5. In a railway sleeping car having wheel trucks near the ends thereof, a roof, side walls, end floorings over the trucks, a lower flooring between the trucks and dependent from the end floorings, an upper flooring between the trucks extending over the lower flooring and in a plane above the end floorings, spaced longitudinally extending panels on each of said floorings forming center aisles and side spaces, bulkheads at the ends of the upper flooring aisle, transverse panels dividing the side spaces into rooms, steps between the lower flooring center aisle and the center aisles of the end floorings, stairways adjacent the center aisle steps leading from rooms on the end floorings to adjacent upper rooms, and archways in the aisle panels of the rooms in which the stairways terminate.

6. In a railway sleeping car having wheel trucks near the ends thereof, a roof, side walls, end flooring over the trucks, a lower flooring between the trucks, an upper flooring between the trucks overlying the lower flooring and in a plane above the end floorings, spaced longitudinally extending panels on each flooring forming center aisles and side spaces, transversely extending panels on each flooring dividing the side spaces into rooms, steps leading from the aisles in the end floorings to the lower aisle, steps in one of the end rooms on each end floor leading to the adjacent end room on the upper flooring, and a longitudinally extending panel in each end flooring room adjacent the steps leading to the upper rooms forming storage chambers adjacent the car side walls.

7. In a railway sleeping car having wheel trucks near the ends thereof, a roof, side walls, end flooring over the trucks, a lower flooring between the trucks, an upper flooring between the trucks overlying the lower flooring and in a plane above the end floorings, spaced longitudinally extending

panels on each flooring forming center aisles therebetween, transversely extending panels on each flooring dividing the spaces between the panels and adjacent car side walls into rooms, 5 steps leading from the aisles in the end floorings to the lower aisle, steps in one of the end rooms on each end floor leading to the adjacent end room on the upper flooring, and longitudinally extending panels in the upper rooms to which the steps 10 lead, said panels and adjacent car side walls forming storage chambers.

8. In a railway sleeping car having wheel trucks near the ends thereof, a roof, side walls, end flooring over the trucks, a lower flooring between the trucks, an upper flooring between the trucks overlying the lower flooring and in a plane above the end floorings, spaced longitudinally extending panels on each flooring forming center aisles and side spaces, transversely extending panels on 15 each flooring dividing the side spaces into rooms, steps leading from the aisles in the end floorings to the lower aisle, steps in one of the end rooms on each end floor leading to the adjacent end room on the upper flooring, and bulkheads closing the ends of the aisle on the upper flooring, 20 said bulkheads being located short of the ends of the upper flooring and the upper flooring being open therebeyond along the aisle portion to provide head clearance for passengers standing in the aisle therebelow adjacent the bottom of the center aisle steps.
